TOILET CLEANING APPARATUS

Frederic H. Lassiter, Los Angeles, Calif.

Application January 31, 1949, Serial No. 73,860

14 Claims.

(Cl. 4—233)

1

This invention relates to a closure and cleaning apparatus for a toilet and is particularly directed to improvements for cleaning a conventional toilet bowl and toilet seat both inside and out and for simultaneously cleaning the floor area about the toilet bowl.

The problem of keeping public and semi-public rest rooms clean has become acute in many areas because of high labor costs and because of inefficient help. It has been recognized that a desirable solution to this problem would involve mechanical means for suitably cleaning the bowl and seat in order to do away with a disagreeable manual task. The proposals which have been advanced have not enjoyed commercial success, however, since most of them have serious shortcomings either from a mechanical standpoint or from the unsatisfactory results achieved. Some of the proposals relate to cleaning of the toilet seat only. Others relate to complicated mechanisms for swinging or moving the toilet bowl bodily into and out of an enclosure.

It is the principal object of my invention to provide a closure and cleaning device for a conventional form of toilet bowl and seat, which device avoids the difficulties present in prior art structures.

Another important object is to provide such a cleaner device which also cleans the floor area around the toilet bowl.

Another object is to provide a closure and cleaner device which can be readily applied to existing installations.

A more detailed object is to provide a retractable hood which may be positioned over a conventional toilet bowl and seat and which is provided with means for cleaning the bowl, seat and floor area around the bowl.

A further object is to provide means for returning the cleaning fluid used for cleaning the exterior of the toilet bowl and the floor area into the interior of the toilet bowl from whence it may be flushed away in the usual manner.

Other and more detailed objects and advantages will appear hereinafter.

In the drawings:

Figure 1 is a front elevation partly broken away showing a conventional toilet bowl and seat and illustrating a preferred embodiment of my invention.

Figure 2 is a sectional elevation taken substantially on the lines 2—2 as shown in Figure 1.

Figure 3 is a sectional elevation taken substantially on the lines 3—3 as shown in Figure 2.

Figure 4 is a side elevation partly in section showing a modified form.

Figure 5 is a sectional detail showing construction of a Venturi pump.

Figure 6 is a sectional detail partly broken away taken substantially on the lines 6—6 as shown in Figure 4.

Referring to the drawings, the toilet device generally designated 10 comprises a conventional

toilet bowl 11 having a base 12 and a tubular outlet 13. A conventional toilet seat 14 rests on the bowl and is secured thereon by means of the usual pivot attachment 15. A water supply pipe 16 supplies water for flushing the toilet when desired. The flush tank and associated equipment are omitted from the drawings for clarity of illustration.

In accordance with my invention, the toilet bowl 11 does not rest directly on the floor 17 but is mounted upon a base plate structure 18 having an opening 19 through which the tubular projection 13 extends. This base plate structure 18 may be provided with a central recess 20 having drain openings 21 in communication therewith. These openings 21 are provided in the upper surface or floor 22 of the base plate structure 18. This upper surface is not horizontal but is inclined slightly so that water drains toward the drain openings 21.

A hood generally designated 23 cooperates with the base plate structure 18 and vertical wall 24 to provide a closure 25 for the bowl 11 and seat 14. This hood 23 includes a pair of stationary side walls 26, a cover 27 and a swinging front plate 28 pivoted to the cover at 29. The cover 27 is pivoted at 30 to the brackets 31 fixed relative to the stationary uprights 32. A handle 33 may be provided on the front wall of the cover 27 if desired for raising the cover from the operative position shown in full lines in Figure 2 to the inoperative position as shown by the dotted lines in Figure 2. However, I prefer to provide power means for raising the cover, and as shown in the drawings this means includes a power cylinder assembly 34. As shown in Figure 3 this assembly 34 is pivotally secured at one end to the stationary brackets 35 and has a projecting piston rod 36 at the other end pivotally attached at 37 to the clevis 38 carried on the cover 27. When hydraulic fluid is admitted into the hydraulic connection 38a and exhausted through the connection 39, the piston rod 36 is caused to move upwardly and pivot the cover to the dotted line position shown in Figure 2. A spring latch 27a may be carried on one of the uprights 32 for resiliently maintaining the cover 27 in raised position. The cover is returned to closed position by admitting hydraulic fluid through the connection 39 and exhausting it through the connection 38a, as will be readily understood.

Any suitable means may be provided for controlling the admission and exhaust of hydraulic fluid, which fluid in this case may be water. A conventional four-way valve may be used if desired or an electric control valve (not shown) operated by the push-button 40 may be employed. The electric circuit for operating the electric control valve may be arranged so that when the push-button 40 is actuated the cover 27 is raised and when the same button is again actuated the cover is lowered. When the cover 27 is raised the swinging plate 28 remains substantially ver-

tical and therefore does not extend out over the bowl 11 or seat 14.

Means are provided for cleaning the bowl 11, seat 14, and that portion of the floor 22 within the enclosure 25. As shown in the drawings this means includes a pair of central circular nozzles 41 and 42 connected by conduit 43 and carried on a common header pipe 44. Encircling the inner nozzles 41 and 42 is a pair of outer ring shaped nozzles 45 and 46 connected by piping 47 and supported on the header 44. The header 44 is provided with a right angle extension 48 pivotally received within a stuffing box 49 and the header 44 is supported by means of a support clip 50 attached to the cover 27. From this description it will be understood that when the cover 27 is raised the support clip 50 causes the nozzles 41, 42, 45 and 46 to be raised about the axis of the right angle extension pipe 48 so that the nozzle assembly generally designated 51 assumes the dotted line position shown in Figure 2 when retracted.

The inner nozzles 41 and 42 are provided with a plurality of openings 52 which are adapted to direct jets of cleaning fluid against the inner portions of the bowl 11 and inner parts of the seat 14. The outer ring nozzles 45 and 46 are also provided with openings 53 adapted to direct jets of cleaning fluid against the outer portions of the seat 14 and also against the outer surface of the upper part of the bowl 11. Additional jet openings 54 may be provided in the lower ring nozzle 46 which direct jets against the floor 22 within the enclosure 25.

The cleaning fluid employed may comprise steam or hot or cold water with or without a suitable detergent. The cleaning fluid is supplied from a suitable chamber 55. This chamber may enclose an electrically heated flash boiler, and if a detergent is to be used the upper portion of the chamber 55 may be occupied by the detergent receptacle. Cold water is admitted into the inlet fitting 56 at the lower end of the chamber 55, and hot or cold water with detergent or hot water or steam without detergent is delivered through the outlet pipe 57 to the stuffing box 19. The flow of water through the inlet fitting 56 is controlled by a suitable valve (not shown) which in turn may be operated by means of the electrical push-button 41. It is contemplated that a suitable interlock will be provided so that it is not possible to operate the cleaning apparatus unless the hood 27 is in operative position.

Means are provided for disposing of the cleaning fluid which collects on the floor 22 within the enclosure 25. As shown in the drawings the floor 22 is inclined so that the cleaning fluid flows toward the base 12 of the bowl 11 and gravitates through the ports 21 into the recess 20. A suction pipe 58 establishes communication between the recess 20 and the screened inlet 59 to the motor driven pump 60. The fluid pumped passes outwardly through the discharge line 61 through the check valve 62 and into the pipe 16 from whence it may be discharged in the usual way through the outlet passage 63 and sewer pipe 64. The motor driven pump 60 is controlled by the push-button 41 so that the pump operates while the cleaning fluid is being sprayed on the bowl, seat and floor. A time delay device may be employed if desired so that the motor driven pump 60 continues to operate for a short time interval after the push-button 41 is actuated to stop the cleaning cycle.

In the modified form of my invention shown in Figures 4 and 5, the motor driven pump 60 is replaced by a Venturi type pump 70 which is connected through supply conduit 71 with the inlet pipe 16 and connected through discharge line 72 and check valve 73 to the supply pipe 16 downstream from the restriction 74. A check valve 75 is also placed in the inlet line 76 which communicates with the recess 20 in the base structure 18. In this form of my invention the cleaning fluid is removed from the recess 20 whenever water flows into the toilet bowl.

The size of the recess 20 is governed by the amount of cleaning fluid which must be disposed of from the recess 20 on each cleaning cycle. A relatively small volume for the recess 20 is sufficient when the motor driven pump 60 is employed, but a larger volume must be provided when the Venturi pump 70 is used because the Venturi pump 70 operates only when the toilet is flushed and therefore a larger volume of cleaning fluid accumulates between cleaning cycles.

It is contemplated that my invention may be employed in connection with new plumbing installations or it may be installed in connection with existing equipment. The base structure 18 can be of split form if necessary, but I prefer to employ an integral unit without the split and to raise the toilet bowl sufficiently to install it between the floor of the room and the toilet bowl. It may be necessary or desirable to employ drying means to follow the cleaning cycle. Compressed air may be piped into the enclosure if desired and arranged to dry the seat after the supply of cleaning fluid to the spray nozzles has been shut off. The control for such drying air would be interlocked with the cleaning cycle so that the air would be turned on after the cleaning fluid is shut off and before the cover 27 is raised.

Having fully described my invention, it is to be understood that I do not wish to be limited to the details herein set forth, but my invention is of the full scope of the appended claims.

I claim:

1. Apparatus for cleaning a toilet seat and bowl in situ, comprising in combination: means forming an enclosure for the bowl and seat, said means including stationary walls and a movable cover; means whereby the cover may be retracted to an inoperative position remote from the bowl and seat; and a retractable spray nozzle assembly within the enclosure and having portions thereof adapted to direct jets of cleaning fluid against the bowl and seat.

2. Apparatus for cleaning a toilet seat and bowl in situ, comprising in combination: means forming an enclosure for the bowl and seat, said means including stationary walls and a movable cover; a spray nozzle assembly having portions thereof adapted to direct jets of cleaning fluid against the bowl and seat; and means whereby the cover and said assembly may be retracted to an inoperative position remote from the bowl and seat.

3. Apparatus for cleaning a toilet seat and bowl in situ, comprising in combination: means forming an enclosure for the bowl and seat, said means including stationary walls and a movable cover; means whereby the cover may be retracted to an inoperative position remote from the bowl and seat; a spray nozzle assembly having a portion thereof adapted to direct jets of cleaning fluid against the bowl and seat; and means whereby the nozzle assembly may be moved to an inoperative position.

4. Apparatus for cleaning a toilet seat and bowl in situ, comprising in combination: means forming an enclosure for the bowl and seat, said means including stationary walls and a pivoted cover; means whereby the cover may be pivoted to an inoperative position remote from the bowl and seat; a spray nozzle assembly having a portion thereof adapted to direct jets of cleaning fluid against the bowl and seat; and attachment means connecting the nozzle assembly for pivotal movement with the cover.

5. Apparatus for cleaning a toilet seat, bowl and floor area around the bowl, comprising in combination: means forming an enclosure for the bowl and seat, said means including stationary walls and a movable cover; a spray nozzle assembly having a portion thereof adapted to direct jets of cleaning fluid against the bowl and seat and against the floor area within the enclosure; and means whereby the cover and said assembly may be retracted to an inoperative position remote from the bowl and seat.

6. Apparatus for cleaning a toilet seat, bowl and floor area around the bowl, comprising in combination: means forming an enclosure for the bowl and seat, said means including stationary walls and a movable cover, said means also including a base structure extending under the bowl and having an inclined floor for drainage, a spray nozzle assembly adapted to direct jets of cleaning fluid against the bowl and seat, the base structure being provided with a recess to receive the cleaning fluid draining from the inclined floor; and means for pumping cleaning fluid from said recess into the interior of the toilet bowl.

7. Apparatus for cleaning a toilet seat, bowl and floor area around the bowl, comprising in combination: means forming an enclosure for the bowl and seat, said means including stationary walls and a movable cover, said means also including a base structure extending under the bowl and having an inclined floor for drainage, a spray nozzle assembly adapted to direct jets of cleaning fluid against the bowl and seat and against the floor area within the enclosure, means whereby the cover and said assembly may be retracted to an inoperative position, the base structure being provided with a recess to receive the cleaning fluid draining from the inclined floor; and means for pumping cleaning fluid from said recess into the interior of the toilet bowl.

8. Apparatus for cleaning a toilet seat, bowl and floor area around the bowl, comprising in combination: means forming an enclosure for the bowl and seat, said means including stationary side walls and a movable cover provided with a hinged front wall, said means also including a base structure extending under the bowl and having an inclined floor for drainage, a spray nozzle assembly adapted to direct jets of cleaning fluid against the bowl and seat, means for retracting the cover and spray nozzle assembly to an inoperative position remote from said bowl and seat.

9. Apparatus for cleaning a toilet seat, bowl and floor area around the bowl, comprising in combination: means forming an enclosure for the bowl and seat, said means including stationary side walls and a movable cover provided with a hinged front wall, said means also including a base structure extending under the bowl and having an inclined floor for drainage, a spray nozzle assembly adapted to direct jets of cleaning fluid against the bowl and seat; pump means for de-

livering cleaning fluid draining from the inclined floor to within the toilet bowl; and means for retracting the cover and spray nozzle assembly to an inoperative position remote from said bowl and seat.

10. Apparatus for cleaning a toilet seat, bowl and floor area around the bowl, comprising in combination: means forming an enclosure for the bowl and seat, said means including stationary side walls and a movable cover provided with a hinged front wall, said means also including a base structure extending under the bowl and having an inclined floor for drainage, and spray means within the enclosure for directing cleaning fluid against the seat, bowl and inclined floor.

11. Apparatus for cleaning a toilet seat, bowl and floor area around the bowl, comprising in combination: means forming an enclosure for the bowl and seat, said means including stationary side walls and a movable cover provided with a hinged front wall, said means also including a base structure extending under the bowl and having an inclined floor for drainage; spray means within the enclosure for directing cleaning fluid against the seat, bowl and inclined floor; and common means for retracting the cover and spray means to an inoperative position remote from said seat.

12. Apparatus for cleaning a toilet seat, bowl and floor area around the bowl, comprising in combination: means forming an enclosure for the bowl and seat, said means including stationary walls and a movable cover, said means also including a base structure extending under the bowl and having an inclined floor for drainage, the base structure being provided with a recess to receive the cleaning fluid draining from the inclined floor; and a Venturi pump actuated by flow of water to the toilet bowl for pumping cleaning fluid from said recess into the interior of the toilet bowl.

13. Apparatus for cleaning the floor area around a toilet bowl, comprising in combination: a base structure extending under the bowl and having an inclined floor for draining; fluid spray means for cleaning the bowl and floor; and means including a pump for delivering fluid draining from the inclined floor into the interior of the toilet bowl.

14. Apparatus for cleaning a toilet seat and bowl in situ comprising in combination: walls forming an enclosure for the bowl and seat; means for moving certain of the walls to expose the bowl and seat for use; a spray nozzle assembly operable within the enclosure and having a portion thereof adapted to direct jets of cleaning fluid against the bowl and seat; and means whereby the nozzle assembly may be moved to an inoperative position.
